UNITED STATES PATENT OFFICE

2,565,939

LINED WATERPROOF CONTAINER

Roderic T. Wriston, Phippsburg, Maine

Application April 10, 1947, Serial No. 740,603

2 Claims. (Cl. 220—65)

1

This invention relates to improvements in kits for transporting toilet articles.

An object of the invention is to provide an improved kit for transporting toilet articles adapted to be placed within a larger handbag and so constructed that no damage may be inflicted upon the articles during transportation.

Another object of the invention is to provide an improved kit for transporting toilet articles including a substantially rigid hollow body having a cover hinged thereto and a soft cushioning lining supported in said body and top solely by means of the contour thereof.

A still further object of the invention is to provide an improved kit for transporting toilet articles including a substantially rigid metal or plastic case having a cover hinged thereto and a locking member therefor, said case and cover being provided with linings of neoprene or some other desired cushioning material which will be shaped to fit the inner surfaces of said case and cover and to be supported therein by the shaping of said parts to provide a waterproof and air-tight case for carrying toilet articles of various types so that the same will not be injured and so that if any liquid in the case should spill it will not leak out of the case to injure other articles carried with the case in a handbag or other piece of luggage.

Another object of the invention is to provide an improved form of kit for transporting toilet articles which will be highly efficient in operation, and relatively inexpensive to manufacture and produce.

Other objects will appear as the description proceeds.

In the accompanying drawings which form a part of this application,

Figure 1 is a perspective view of the improved kit for transporting toilet articles, showing the same in locked position;

Figure 2 is a sectional view taken on the line 2—2 of Figure 1, and

Figure 3 is an enlarged detailed sectional view through a portion of the case and cover showing the lock or latch mechanism therefor in unlocked position.

Like characters of reference will be used throughout the following specification and the accompanying drawings to designate corresponding parts.

In carrying out the invention, there is provided a substantially rectangular shaped rigid case generally designated by the reference numeral 1 having a cover 2 therefor secured to said case by means of the hinge or hinges 3.

2

U-shaped keeper 4 is supported upon the case 1 or formed integrally therewith, and cooperates with the pivoted operating finger 5 supported upon the front edge of the cover 2, said finger 5 pivotally supporting the U-shaped locking loop 6 which is adapted to be disposed over the U-shaped keeper 4 when the pivoted operating finger 5 is in released position, whereupon when said finger 5 is pushed upwardly, as illustrated in Figures 1 and 2, tension will be placed upon the U-shaped locking loop 6 to securely lock the cover 2 upon the case 1. A tongue 20 is formed on the cover 2 adjacent the pivoted operating finger 5 and is adapted to be received in the notched seat or receptacle 21 formed in the upper edge of the case 1, as clearly illustrated in Figures 1 and 2 of the drawings.

The upper edge of the case 1 is provided with an interiorly disposed U-shaped lip 7, while a similar formed U-shaped lip 8 is formed about the inner lower edge of the cover 2 to lie parallel with said lip 7 when the cover is in closed position upon the case 1, as illustrated in Figure 2 of the drawings.

25 A lining 9 of neoprene or any other desired cushioning material is disposed within the case 1, and is provided with a peripheral bead or flange 10 adapted to be received in the U-shaped lip 7 formed about the inner periphery of said case 1, with the lining 9 lying parallel with all parts of the inner surface of said case 1.

A similarly formed cover lining 11 is provided, being formed of neoprene or any other suitable cushioning material and is likewise provided with the peripheral bead 12 adapted to be disposed or received within the U-shaped lip 8 formed about the periphery of the cover 2, whereby when said cover 2 is closed upon the case 1, an air-tight and water-tight seal will be made between said parts, which will trap air within the case to support and force the linings 9 and 11 into contact with the case and cover to hold the same in position without the use of any form of adhesive or other type of fastening means.

45 From the foregoing description, it will be apparent that there has been devised a highly efficient form of kit for transporting toilet articles which will be relatively inexpensive to manufacture and produce.

If desired, the kit may be made out of plastic or light metal, or from any desired material which will be resistant to crushing when it is placed within a handbag or other piece of luggage. Furthermore, the case and cover may be 55 painted any desired color if desired, and will provide an efficient form of waterproof and airproof

container for carrying the necessary toilet articles customarily used in travelling.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A carrying case comprising a pair of complementary shells, U-shaped grooves formed in the adjacent edges of said shells, said grooves being disposed in aligned registry when the shells are secured together and forming a channel, an inner flexible lining for each shell section, said lining having beaded edges frictionally fitted in the grooves of the shell sections whereby an air-tight seal will be effected at the adjacent edges of the shell sections when the sections are secured together.

2. A carrying case comprising a main section having upstanding walls and a lid section hinged-ly connected thereto and having depending walls, latch means for said sections, U-shaped grooves formed on the free edges of said sections, said

grooves being disposed in aligned registry when the sections are secured together to form a channel, a flexible lining for the main section and a similar flexible lining for the lid section, beaded marginal edges on said linings frictionally fitted in the grooves for retaining the linings in contact with the inner surfaces of the sections, said beaded edges being compressed together to form an air-tight seal when the edges of the walls of the sections are brought together.

RODERIC T. WRISTON.
